PRESS WITH DIE CUSHION

Walter Ernst, Mount Gilead, Ohio, assignor to
The Hydraulic Development Corp. Inc., Wil-
mington, Del., a corporation of Delaware

Application May 3, 1940, Serial No. 333,211

9 Claims.

(Cl. 113—45)

The present invention relates to presses, and in particular to hydraulic presses with die cushion.

It is an object of the invention to provide a press with a die cushion so as to allow operation of the press selectively with or without die cushioning effect.

It is a further object of the invention to provide a press with a die cushion cylinder and ejector which will allow operation of the press selectively with or without both the die cushion and the ejector.

Another object of the invention consists in providing a press having a die cushion and an ejector, which press may be operated selectively with ejector but without die cushion, or with or without both the die cushion and ejector.

A still further object of the invention consists in providing a press with a die cushion and an ejector plunger in which the ejector plunger may, if desired, also act as a cushioning plunger.

These and other objects and advantages of the invention will appear more clearly from the following description in connection with the accompanying drawings in which:

Figure 1 illustrates in front elevation, an embodiment of the press according to the invention.

Figure 2 shows, on a somewhat larger scale, the upper portion of the press illustrated in Figure 1.

Figure 3 illustrates, likewise on a larger scale, the lower portion of the press of Figure 1.

Figure 4 is a section along the line 4—4 of Figure 1.

Figures 5 and 6 show, diagrammatically, the press during its downward or drawing stroke, and

Figures 7 and 8 show likewise, diagrammatically, the press during its upward or return stroke.

The press as illustrated in the drawings comprises a base 1 and a press head 2 connected with the base 1 by strain rods 3, 3a, 3b and nuts 4, 4a and 5, 5a. The press head 2 comprises a main cylinder 6 and auxiliary cylinders 7, 7a. Reciprocably mounted in the main cylinder 6 is a drawing ram 8 supporting the press platen 9. The platen 9 carries clamping cylinders 10 closed at their ends by packing material 11, compressed by glands 12. Through the glands 12 and packing material 11 of each clamping cylinder passes a clamping plunger 13 supporting a clamping platen 14. The clamping platen 14 has arms 15 (one only shown in the drawings) connected with rods 16 passing through arms 17 of the press platen and carrying at its upper end a nut 18 so as to cause the press platen 9 to lift the clamp-

ing platen 14 when the arms 17 abut the nuts 18. Connected with each clamping cylinder 10 is a hollow plunger 19 reciprocable in its respective auxiliary cylinder 7, 7a and effecting a communication between the respective cylinders 10 and 7, 7a.

The main cylinder 6 carries at its upper end a surge valve 20 (see Figure 2). This surge valve is mounted within the surge tank or fluid reservoir 21 on top of the press head 2 and is of the type disclosed in the Ernst Patent 1,892,568 issued December 27, 1932. The surge valve 20 consists of a casing 22 bolted to or otherwise connected with the main cylinder 6. The casing 22 comprises a longitudinal bore 23 and in alignment therewith a bore 24 of somewhat larger diameter. The bore 24 is closed by a closure 25 having an aperture 26 therein. The closure 25 is engaged by one end of a spring 27, the other end of which engages a valve disc 28 urged by the spring 27 against the valve seat 29, so as to close communication between the bores 24 and 23. The bore 24 communicates with the interior of the cylinder 6 through lateral bores 30. The valve disc 29 is adapted to be engaged by a plunger 31 reciprocably mounted in the bore 23 and carrying at its upper end a piston 32 urged by means of a spring 33 against the upper closure 34 of the casing 22. The bore 23 communicates through bores 35 with the interior of the surge tank 21. The upper closure 34 of the surge valve 20 has an aperture 36 therein adapted to effect communication between the bore 23 and a conduit 37 comprising a relief valve 38 for releasing undue pressure in the conduit 37.

A conduit 39 branches off from the conduit 37 and leads by way of the conduit 40 to the cylinder bore 41 of the main cylinder relief and pump by-pass valve generally designated as 42. This main cylinder relief and by-pass valve is disclosed and claimed in the Ernst Patent No. 1,956,758 issued May 1, 1934, and provides for a drop in pressure within the upper part of the main cylinder 6 at the instant of reversal of the drawing ram 8. Such a drop in pressure is necessary before the surge valve disc 28 can be moved downwardly by the surge valve plunger 31. The valve 42 also takes care of the discharge of the variable delivery pump 43 during a fraction of a second which is required for the forcible opening of the surge valve 20 by the surge valve plunger 31.

The main cylinder relief and by-pass valve 42 comprises a second cylinder bore 44. Reciprocably mounted in the cylinder bore 41 of the

valve 42 is a valve member 45 with two pistons 46 and 47. Connected with the piston 47 is an abutment 48 engaged by a spring 49 urging the valve member 45 toward the right and engaging with its other end the wall 50 of the valve 42. Similarly, a valve member 51 is reciprocably mounted in the cylinder bore 44 and comprises two pistons 52 and 53. Piston 53 is likewise connected with an abutment 54 which is engaged by a spring 55 urging the valve member 51 toward the right and engaging with its other end the wall 56 of the valve 42.

The chamber 57 housing the spring 49 communicates with the tank 21 through an aperture 58, while the chamber 59 housing the spring 55 communicates with the tank 21 through an aperture 60. Apertures 61 and 62 in the valve 42 are adapted respectively to effect communication of the cylinder bores 41 and 44 with the tank 21. The valve 42 furthermore comprises a channel 63 adapted to effect communication between the cylinder bores 41 and 44. A conduit 41a leads from the bore 41 of the valve 42 to a conduit 65a, which leads on one hand through the port 29a to the upper portion of the main cylinder 6, while on the other hand it communicates with bores 68a and 69a of the connecting members 70a and 71a and the bore 73a passing through the strain rod 3a. The bore 73a then communicates through the bores 75a and 76a with a conduit 79a. A conduit 96 branches off from the conduit 41a and comprises a relief valve 38a for relieving undue pressure in the conduits 41a and 96.

The cylinder bore 44 of the main relief and bypass valve 42 communicates through a conduit 64 with the conduit 65 leading to the port 66 of the variable delivery pump 43. The conduit 65 communicates through the port 66 with the upper portion of the main cylinder 6. The other port 67 of the pump 43 communicates through a conduit 67a with the bores 68 and 69 in the connecting members 70 and 71, and a bore 73 through the strain rod 3.

The bore 73 communicates through bores 75 and 76 in connecting members 77 and 78 with conduits 79 and 80. The conduit 79 leads to a two-way valve, generally designated 81, which comprises a cylinder 82 closed at its ends by packing material 83 and 84 compressed by glands 85 and 86 respectively.

The cylinder 81 comprises 3 aligned bores, 87, 88 and 89, having a diameter corresponding to the diameter of the pistons 90 and 91 connected with the push rod 92. The bores 87 and 88 are separated from each other by a chamber 93 having a larger diameter than the bores 87, 88 and 89 and communicating with a conduit 94. Similarly, the bores 88 and 89 are separated from each other by a chamber 95 having a larger diameter than the piston 90 and communicating with a conduit 79 leading to the bores 75 and 76 in the connecting members 77 and 78.

The push rod 92 carries, adjustably mounted thereon, sleeves 97 and 98, each having a circular groove 99 and 100 respectively. The grooves 99 and 100 may be engaged by a pin 101 carried by an arm 102 supported by the press platen 9. The push rod 92 is guided in a sleeve 103, connected by means of arm 104 with the press head 2.

Also connected with the press head 2 is a sleeve 105 through which passes an adjusting rod 106 carrying at its upper end an adjustable collar 107 adapted to be engaged by a lever arm 108 of a 75

lever 109. The lever 109 is shiftably mounted on a stud 110 and is connected by means of its arm 111 and a connecting rod 112 with the armature 113 of a solenoid 114. The solenoid 114 is connected by conductors 115 and 116 with an electric circuit (not shown), which is connected with the conductors 117 and 118 leading to a switch in a tonnage control valve 119, which at the attainment of the predetermined pressure closes the circuit thereby energizing the solenoid 114. The tonnage control valve 119 is of the type disclosed in United States patent application to Ernst, Serial No. 214,772, filed June 20, 1938.

The adjusting rod 106 is provided with a thread 120 and carries an adjusting nut 121 adapted to be engaged by a collar 122 carried by an arm 123 connected with the press platen 9. The nut 121 is prevented from rotation by a pin or other guide means (not shown), so that a rotation of the rod 106 will cause the nut to move upwardly or downwardly in accordance with the direction of rotation of the rod 106. The adjusting rod 106 has an extension 124 connected by a gear system (not shown), with the handwheel 125 supported by the base 1 so that rotation of the handwheel 125 causes an adjustment of the nut 121 relative to the thread 120.

The lever 109 is connected by a link 126 with a lever 127 adjustable about the stud 128 and connected by links 129 and 130 with a control rod 131 of the servo-motor 132 pertaining to the variable delivery pump 43 and adapted to control the flow of fluid thereof. The control rod 131 is engaged by one end of a spring 133 having its other end connected to a fixed point 134 and urging the control rod 131 toward the left so as to cause the variable delivery pump to deliver fluid through the conduit 67a.

The press head 2 supports a two-way valve 135 which in its construction corresponds to the two-way valve 81. The two-way valve 135 comprises a cylinder 136 having three aligned bores 137, 138 and 139 having a diameter corresponding to the diameter of the pistons 140 and 141 connected with a reciprocable push rod 142. The push rod 142 passes through packing material 143 compressed by a gland 144 and carries adjustably mounted thereon collars 145 and 146. The collars 145 and 146 are respectively provided with grooves 147 and 148 cooperating with a pin 149 carried by an arm 150 supported by the press platen 9. The push rod 142 is guided in sleeves 151 and 152 connected with the press.

The bores 138 and 139 are separated from each other by a chamber 153 having a larger diameter than the pistons 140 and 141 and communicating through a conduit 154 with a conduit 155 comprising check valves 156 and 157 which open in the direction of the arrows B and C. A conduit 156a leads from the conduit 155 into the auxiliary cylinder 7. The conduit 155 furthermore comprises a safety valve 158 which opens into the tank 21 when the pressure in the conduit 155 exceeds a predetermined value.

A conduit 159 comprising check valves 160 and 161, opening in the direction of the arrows pertaining thereto, branches off from the conduit 155 and leads to a conduit 162 communicating with the interior of the auxiliary cylinder 7a.

The cylinder bores 138 and 137 of the two-way valve 135 are separated from each other by a chamber 163 having a diameter larger than that of the pistons 140 and 141 and communicating through a conduit 164 with the tank 21.

Mounted also in the tank 21 is a check valve

165 comprising a chamber 166 which communicates through a conduit 167 with the conduit 39 leading to the bore 68 in the connecting member 70. The chamber 166 is adapted to communicate through a bore 168 with the tank 21 when the ball 169 is lifted from its valve seat. The ball 169 may, if desired, be continually held on its valve seat by moving the rod 170 downwardly until its lower end, or a washer connected therewith, abuts the ball 169 and presses it downwardly. This would prevent the oil in the tank from escaping through the conduit 39, in case some of the pipe connections, e. g. the members 70 or 71, have to be removed for repairing or similar purposes.

The tank 21 further comprises a check valve 171 opening in the direction as indicated by the arrow pertaining thereto and adapted to effect communication between the conduit 172 and the tank 21. The conduit 172 communicates with a relief valve 173 and through conduits 174, 175 and 176 with the relief valves 177, 178 and 179. The said relief valves are all of the same structure so that description of one relief valve will be sufficient.

As will be seen from the drawings, the relief valve 177 comprises a casing 219 having reciprocably mounted therein a piston 220 connected with a piston rod 221 which is reciprocable in a bore 222 of a member 223 connected with the casing 219. The piston 220 is engaged by one end of a spring 224 which urges the piston 220 downwardly so that the piston rod 221 closes communication between the bore 222 communicating with the conduit 180 and the conduit 225 communicating with the conduit 173. The other end of the spring 224 is engaged by a washer 226 which is adjustable by means of the screw 227, so as to vary the thrust of the spring and thereby the pressure at which the relief valve will operate. The screw 227 is surrounded and protected from undue manipulation by a cap 228.

Each of the relief valves 173, 177, 178 and 179 communicates with an auxiliary cylinder. In the drawings, only relief valve 177 is shown communicating through a conduit 180 with the auxiliary cylinder 1a, whereas the auxiliary cylinder 1 communicates through the conduit 181 with the relief valve 178.

Connected with the press platen 9 are push back plungers 182 which pass through glands 183 and packing material 184, compressed thereby, into push back cylinders 185 which communicate with each other through conduits 186 and 80. The push back cylinders 185 are supported by the base 1, which also carries a cushioning cylinder 187.

Reciprocably mounted in the cushioning cylinder 187 is a plunger 188 having a bore 189 therethrough. The plunger 188 carries an ejector 190 with ejector members 191 passing through a plate 192 bolted to or otherwise connected with the base 1. The plate 192 carries an adjustable stop 193 so as to determine the upper-most position of the ejector 190.

The bore 189 cooperates with a stationary plunger 194 having a bore 195 therethrough. The bore 195 communicates through a bore 196 in a connecting member 197 with the conduit 94 comprising a straightway valve 198 and a safety valve 199. The safety valve 199 is adapted by means of a conduit 200 to communicate with the tank 21, when the pressure in the bore 195 exceeds a predetermined value.

In the conduit 200 adjacent the tank 21 is 75

provided a check valve 201 opening in the direction of the arrow pertaining thereto. This check valve 201 allows the repair and removal of the conduit 200 without having to empty the tank 21. Branching off from the conduit 200 is a conduit 202 receiving the leakage between the plunger 188 and the cylinder 187 and communicating with a safety valve 203, which in its turn, is adapted to communicate with a bore 204 connected to the port 205 in the lower portion of the cushioning cylinder 187.

The bore 204 provided in the hollow arm 206 leads to a port 207 in the die cushion check valve, generally designated 208. The check valve 208 comprises a valve member 209 having a piston 210 reciprocable in the bore 211 of the check valve 208. The check valve 208 comprises a further bore 212 communicating with the conduit 79a and adapted also to communicate with the port 207 when the valve member 209 is lifted from its valve seat 213. The upper portion of the valve 208 has threaded therein an adjusting rod 214 adjustable by rotation of the handwheel 215 so as to press the valve member 209 upon its seat 213.

The bore 212 in the valve 208 communicates through a conduit 216 with a chamber 217 of the die cushion relief valve 218. The construction of the valve 218 corresponds to the construction of the relief valve 177, so that a further description of the valve 218 is not necessary. A conduit 229 leads from the bore 204 to the relief valve 218, and the relief valve 218 is adapted to effect communication between the conduit 229 and the conduit 216. The relief valve 218 may be by-passed by a conduit 230 adapted to communicate with the conduits 229 and 216 through a straight way valve 231.

A valve 232 corresponding in its construction to the valve 208 is provided in a conduit 233 communicating on one end with the conduit 94 and on the other end with the conduit 79. The valve 232 opens in the direction of the arrow D.

A further conduit 234 likewise communicating with the conduits 94 and 79 comprises a relief valve 235 which may likewise correspond in its construction to the relief valve 177.

Operation

The operation of the device is as follows: Assuming that the press and its parts occupy the position shown in Figure 1 and that it is desired to operate the press together with the die cushion and the ejector. To this end, the operator closes or locks the valve 232, which as previously mentioned corresponds in its construction to the valve 208. The electric circuit comprising the solenoid 114 is closed by any desired means, for instance by the operation of a push button. This causes energization of the solenoid 114 so that the armature 113 will be attracted and by means of the lever mechanism 111, 126, 131 moves the variable delivery pump 43 into position for delivering pressure fluid through the conduit 65. Pressure fluid now enters the upper portion of the main cylinder 6, and while the press ram slides down by gravity, fills the space above the press ram 8 with fluid. This fluid is supplemented by fluid from the tank 21 which flows through the opening 35, the now opened surge valve 20 and the bores 30.

Pressure fluid through the conduit 65 also acts upon the piston 52 of the main cylinder relief and by-pass valve 42 and moves the valve mem-

ber 51 toward the left against the thrust of the spring 55.

Liquid from the push back cylinder 185 may escape through the conduits 80 and 186, the bores 76, 75, 73, 71 and 68 and the conduit 67a to the suction side 67 of the variable delivery pump 43.

As soon as the ram 8 moves downwardly, thereby also moving the hollow plungers 19 downwardly, a suction effect is produced in the auxiliary cylinders 1, 1a. Shortly after the starting of the downward movement of the ram 8, the pin 101 engages the groove 99 of collar 98 on the push rod 92, while moving downwardly pushes the rod 92 likewise downwardly so that the piston 91 connected with the push rod 92 shuts off communication between the conduits 94 and 79.

The straight way valve 198 is supposed to be open while the straight way valve 231 is supposed to be closed.

When the clamping platen 14 approaches the workpiece, the pin 149 engages the grooves 141 of the collar 145 and while moving further downwardly moves the push rod 142 likewise downwardly so that at the time the press platen engages the workpiece the piston 140 has closed off communication between the conduits 154 and 164. Pressure now builds up in the main cylinder 6 and also in the clamping cylinders 10 and auxiliary cylinders 1, 1a. The pressure built up within the upper part of the main cylinder 6 closes the surge valve 20 by pressing its valve disc 28 against its valve seat 29.

Undue pressure in the cylinders 10, 1, 1a is relieved through the corresponding relief valves 177, 178, 179, 173. Since the said relief valves are adjustable individually, different clamping pressures may be exerted in the different clamping cylinders. When the push rods 92 and 142 have been moved to their lowermost position by the pins 101 and 149 respectively, the pins 101 and 149 click out of their respective collars 98 and 145 and during the further downward movement of the push rods 92 and 142 slide over and beyond their respective collars 97 and 146.

While the press platen 9 with the die 236 connected therewith begins its drawing operation proper, the die 231 (see Figures 4 and 5) supported by the cushioning plunger 188 is gradually pressed downwardly so that pressure in the cushioning cylinder 187 builds up. This pressure presses valve member 209 upon its valve seat 213 thereby closing communication between the port 207 and the bore 212. In this way the pressure fluid in the cushioning cylinder 187 acts as a cushion. Any excess pressure in the cushioning cylinder 187 escapes through the conduit 229, the relief valve 218 and conduit 216, the conduit 79a, the bore 73a, the bore 68a into the conduit 65a, and from there into the upper portion of the cylinder 6. If for some reason the relief valve 218 should not operate, or undue pressure should build up in the cushioning cylinder 187, the safety valve 203 will come into action and relieve undue pressure in the cushioning cylinder 187 through the conduits 202 and 200, into the tank 21. Pressure likewise builds up in the bore 189 which also acts as a cushioning cylinder. The excess pressure in the cushioning cylinder bore 189 is relieved through the conduit 94, the conduit 234, the relief valve 235 and the conduit 79, from where it flows through the bores 76, 75, 73, 69 and 68 to the suction side of the variable delivery pump 43. Any undue pressure may be

relieved through the safety valve 199 and the conduit 200 into the tank 21.

As soon as the drawing operation is finished, or in other words, the ram 8 has reached its predetermined lowermost position, the pressure built up in the main cylinder 6 actuates the tonnage control valve 119 so as to disengage the switch connected therewith and to break the circuit comprising the solenoid 114. As a result thereof, the solenoid 114 is de-energized and the spring 133 now reverses, by means of the push rod 131, the delivery direction of the variable delivery pump 43 so that the latter now delivers pressure fluid through the port 67, while its port 66 becomes the suction side.

However, since at this time the surge valve 20 is closed so that no fluid can escape from the upper portion of the main cylinder 6, the retraction movement of the ram 8 is prevented for the fraction of a second. Fluid pressure in the conduit 67a is then conveyed through the conduits 39 and 40 to the piston 46 of the valve member 45 in the main cylinder relief and by-pass valve 42. The pressure upon the piston 46 moves the valve member 45 with the piston 47 toward the left thereby establishing communication between the conduit 41a and the cylinder bore 41 and the aperture 61 in the valve 42, so that pressure fluid may escape from the upper portion of the cylinder 6 through the port 29a the conduit 41a the bore 41 and the aperture 61 into the tank 21.

The leftward movement of the piston 46 also establishes communication between the bore 41 and the channel 63, and since previously the piston 53 had moved toward the left, fluid may escape from the conduit 40 through the bore 41, the channel 63, the bore 44 and the aperture 62, into the fluid tank 21. When a portion of the liquid above the ram 8 is thus released into the tank 21, the pressure in the conduits 39 and 37 acting upon the piston 32 of the surge valve, presses the piston 32 downwardly and by means of the piston rod 31 moves the valve disc 28 downwardly so as to establish communication between the fluid tank 21 and the upper portion of the main cylinder 6 through the bores 30 and 35.

Due to the pressure fluid delivered by the variable delivery pump 43 into the push back cylinders 185 through the conduit 67a, the bores 68 and 69, 75, 76 and 186, the push back plungers 182 are gradually lifted so that the ram starts its actual retraction stroke.

Since previously communication was cut off between the conduits 94 and 79 through the valve 81, and since furthermore the valve 232 is kept closed by the fluid pressure in conduit 79, the plunger 188 remains at its lower position during the initiation of the retraction stroke of the ram 8. However, when the clamping platen 14 has released the workpiece, the pin 101 engages the groove 100 of the collar 97 and, while the press platen 9 further moves upwardly, lifts the push rod 92 thereby moving the pistons 91 and 90 connected with the push rod 92 into their uppermost position. As a result thereof communication is effected between the conduits 94 and 79 through the two-way valve 81 so that pressure fluid passes from the conduit 79 through the two-way valve 81, the conduit 94, the straight-way valve 198, the bore 195 in the plunger 194 and into the bore 189, thereby lifting the plunger 188 with the ejector 190 to eject the workpiece. While the plunger 188 is moving upwardly, the valve member 209 opens due to the suction effect in the bore 104, and fluid from the upper portion of the cylin-

der 6 passes through the conduit 65a, the bores 68a, 69a, 73a, 76, 79a, 212 and 204 into the cushioning cylinder 187. At about the same time, when the pin 101 engages the groove 100 of the collar 97, the pin 149 will engage the groove 148 of the collar 146 and by moving upwardly, will lift the push rod 142 with its pistons 140 and 141 so as to establish communication between the conduits 154 and 164 through the two-way valve 135. This allows the pressure fluid in the auxiliary cylinders 7, 7a to escape through the conduits 156a, 155, 154 and 164 into the fluid tank 21. When the ram approaches its uppermost position the collar 122 engages the nut 121 on the threaded rod 106 and shifts by means of the collar 107, connected with the rod 106, the lever arm 108 so as to move the pump 43 into no-delivery position by means of the lever system 126 to 131. The press is now ready for a further working stroke.

If full automatic operation of the press is desired, in other words if at the end of the retraction stroke the press shall automatically begin a new working stroke, it is merely necessary to provide the push rod 106 with contacting means which in the uppermost position of the rod 106 closes the circuit comprising the solenoid 114.

If it is desired to operate the press without both the die cushion and the ejector, the plunger 188 is first moved downwardly either by the press platen 9 or by opening a drainage valve (not shown) provided in the bottom of the cushioning cylinder 187 when the plunger 188 is in its lower position the handwheel 215 of the valve 208 is turned so as to press the valve member 209 by means of the locking rod 214 on its seat 213, thereby locking or closing the valve 208. Furthermore the valve 231 is to be opened while the valve 198 is to be closed.

With regard to the valve 232, which as previously mentioned, corresponds in its structure to the valve 208, it is immaterial in this instance whether it is locked or opened.

By closing the circuit comprising the solenoid 114, the working stroke of the ram 8 is initiated as previously described. However, when during the retraction stroke of the ram 8, after the clamping platen 14 has released the workpiece, the pin 101 engages the groove 100 of the push rod 92 and shifts the pistons 91 and 90 to their uppermost position, no pressure fluid can enter the bore 195 to lift the plunger 188 since the straightway valve 198 is closed. Similarly, fluid pressure is prevented by the check valve 208 from passing from the conduit 212 into the cushioning cylinder 187. Consequently, the plunger 188 with the ejector 190 remains in its lower position.

The plunger 188 may at the end of the retraction stroke be lifted to its uppermost position, if desired, by unlocking the valve 208 and opening the straight-way valve 198. This would cause pressure fluid from the push back cylinders 185 to flow through the conduits 79 and 94 and the bore 195 into the bore 189 to lift the plunger 188 while fluid from the bores 68a, 69a, and 73a would pass through the conduit 79a the bore 212 and 204 into the push back plunger 187 to fill the space below the plunger 188. As a consequence of this movement, the ram 8 would sag somewhat, which would allow the spring 133 to move the variable delivery pump 43 into fluid delivery position to deliver fluid into the push back cylinders 185 to return the ram 8 into its uppermost position, whereupon the pump 43 as previously explained, will be again moved to no-delivery position.

To use the press with ejector but without die cushion, the handle 215 of the valve 208 is turned so as to release the valve piston 210, or in other words to unlock the valve 208. Furthermore, the valve 232 is to be unlocked and the straight-way valves 231 and 198 are to be opened.

The first part of the downward stroke of the ram 8 up to the time when the die 236 engages the workpiece, is the same as described in connection with the operation of the press when using both the die cushion and the ejector.

However, when the die 36 engages the workpiece and actually begins its drawing operation, no pressure will prevail in the bore 189 of the plunger 188 and in the cushioning cylinder 187, since the fluid expelled from the bore 189 during the drawing operation lifts the valve member in the valve 232, which valve member corresponds with the valve member 213 of the valve member 208, and escapes through the conduit 79, the bores 73, 69 and the conduit 67a to the suction side of the variable delivery pump. The fluid expelled from the cushioning cylinder 187 escapes through the port 205, the bore 204, the conduit 229, the straight-way valve 231, the conduit 216 and the conduit 79a into the bore 75 from where it flows through the strain rod 3 and the conduit 65a into the uppermost portion of the cylinder 6. Consequently, there is no cushioning effect during operation of the press.

The retraction stroke is initiated as previously described. When the clamping platen 14 has released the workpiece, the pistons 91 and 90 connected with the push rod 92 are lifted, as likewise described above, so that pressure fluid from the push back cylinders passes through the conduits 186 and 79 through the two-way valve 82, the conduit 94, the straight-way valve 198 and the bore 195 into the bore 189, where it lifts the plunger 188 with the ejector 190. The space below the plunger 188 is filled with liquid from the conduit 79a through the valve 208, as previously explained.

The ejector thus ejects the workpiece.

It will be understood that I desire to comprehend within my invention such modifications as come within the scope of the claims and the invention.

Having thus fully described my invention, what I claim as new and desire to secure by Letters Patent, is:

1. In combination in a press, a fluid operable pressing plunger, fluid supply means for supplying fluid to said pressing plunger to operate the same, die cushioning means adapted to cooperate with said pressing plunger, relief valve means associated with said die cushioning means for relieving pressure therefrom when the pressure in said cushioning means exceeds a predetermined value, ejector means for ejecting a workpiece after it has been drawn, a pair of check valves arranged in conduits communicating with said fluid supply means and respectively leading to said cushioning means and said ejecting means, controlling means for making said check valves inoperative, and a pair of shutoff valves respectively connected to said cushioning means and said ejecting means, said valves and said controlling means being adapted to control the operation of said cushioning means and ejector means so as to allow operation of the press selectively with ejector but without die cushion, or with or without both the die cushion and the ejector.

2. In combination in a press, a main cylinder, a fluid operable drawing plunger reciprocable in

said main cylinder, a die cushioning cylinder, a cushioning plunger reciprocable in said die cushioning cylinder and provided with a fluid chamber, a piston adapted to be telescoped into said fluid chamber, a fluid source to supply fluid to said die cushioning cylinder, pressure fluid supply means for supplying pressure fluid to said fluid chamber independently of the supply of fluid to said cushioning cylinder, controlling means for maintaining a predetermined pressure in said cushioning cylinder and valve means adapted to by-pass said controlling means for connecting said cushioning cylinder with an exhaust without affecting the pressure condition in said fluid chamber, whereby said cushioning plunger may selectively be operated during a pressing cycle as an ejector but without substantial cushioning effect.

3. In a press having a pressing plunger with fluid operable advancing and retracting means for reciprocating said plunger, a fluid operable die cushioning plunger reciprocable in a cushioning cylinder and provided with a fluid chamber, a piston adapted to be telescoped into said fluid chamber, said cushioning plunger being adapted to cause a cushioning effect during the pressing stroke and to act as ejector during the retraction stroke of said pressing plunger, adjustable relief valve means responsive to a predetermined pressure in said cushioning cylinder for relieving pressure therefrom, a check valve interposed between said advancing means and said cushioning cylinder and being adapted in response to a retraction stroke of said pressing plunger to allow passage of fluid therethrough from said pressing plunger to said cushioning cylinder but not vice versa, locking means for preventing the flow of fluid through said check valve in either direction, a first shutoff valve adapted to by-pass said check valve, and a second shutoff valve interposed between said fluid chamber and said retracting means for selectively establishing or interrupting communication between said fluid chamber and said retracting means, said locking means and said shutoff valves being operable selectively to allow operation of the press with or without cushioning effect and actuation of said ejector.

4. In a press having a pressing plunger with fluid operable advancing and retracting means for reciprocating said plunger, fluid operable combined die cushioning and ejecting means, fluid supply means for supplying fluid to said plunger reciprocating means and said cushioning and ejecting means to actuate the same, control valve means responsive to the travel of said pressing plunger for interrupting hydraulic communication between said fluid supply means and said die cushioning means at a predetermined point of the working stroke of said plunger, and for effecting communication between said ejecting means and said fluid supply means at a predetermined point of the retraction stroke of said plunger, a check valve arranged to allow fluid to flow from said retracting means to said ejecting means irrespective of the position of said control valve means, locking means associated with said check valve to lock the same in closed position, to prevent said last mentioned flow, a pressure relief valve hydraulically connected with an exhaust and said cushioning means, and a shutoff valve for by-passing said relief valve, whereby said shutoff valve is adapted in cooperation with said check valve selectively to allow operation of said ejecting means with or without actuation of said cushioning means.

5. In combination in a press, a main cylinder, a press ram reciprocable in said main cylinder to perform a pressing and a retraction stroke, fluid supply means for supplying fluid to said main cylinder to actuate said ram, a die cushioning cylinder-piston-assembly with a fluid operable member acting as ejector during the retraction stroke of said ram, relief valve means for relieving pressure fluid from said cushioning cylinder-piston-assembly in excess of a predetermined pressure, a check valve for by-passing said relief valve means to allow free escape of fluid from said cushioning cylinder-piston-assembly during the pressing stroke of said press ram, thereby preventing said member from acting as cushioning member, and locking means associated with said check valve for selectively locking the same in closed position to prevent said free escape, thereby selectively causing said member during one and the same cycle to act as ejector only or to exert a cushioning effect and subsequently to act as ejector.

6. In combination in a press, a reciprocable press ram, means for supplying fluid to said ram to actuate the same, a fluid operable plunger operable as ejector for ejecting a work piece during the retraction stroke of said ram and also operable selectively as cushioning means during the advancing stroke of said ram, controlling means responsive to the movement of said ram for controlling the flow of fluid to and from said plunger, a check valve for allowing free escape of fluid from said plunger, locking means for making said check valve ineffective to prevent said free escape, and means responsive to a predetermined pressure acting on said plunger for releasing pressure therefrom in excess of said predetermined pressure.

7. In combination in a press, a reciprocable ram, means for supplying fluid to said ram for actuating the same, a fluid operable plunger operable selectively as cushioning means during the pressing stroke of said ram and as ejector for ejecting a work piece during the retraction stroke of said ram, a pressure relief valve for relieving pressure from said plunger in excess of a predetermined pressure acting thereupon, control valve means movable in response to the travel of said ram from a first position into a second position during the pressing stroke of said ram for preventing free escape of fluid from said plunger through said control valve means, to actuate said plunger as cushioning means, and from said second position into said first position during the retraction stroke of said ram to admit pressure fluid to said plunger for actuating the same as ejector, conduit means for hydraulically connecting said control valve means with said plunger, and a shutoff valve in said conduit means and interposed between said control valve means and said plunger, said shutoff valve being movable selectively into closing position for making said plunger ineffective as ejector and cushioning plunger.

8. In combination in a press, a main cylinder, a fluid operable press plunger reciprocable in said cylinder, a die cushioning cylinder-piston assembly, an ejector cylinder-piston-assembly, one element of said cushioning cylinder-piston-assembly and of said ejector cylinder-piston-assembly being stationary and the respective cooperating elements of said cushioning and ejector cylinder-piston-assemblies being movably connected with each other, a fluid source for supplying fluid to said die cushioning cylinder-piston-assembly,

pressure fluid supply means for supplying pressure fluid to said ejector cylinder-piston-assembly independently of the supply of fluid to said cushioning cylinder-piston-assembly, control means for maintaining a predetermined pressure in said cushioning cylinder-piston-assembly, and valve means adapted to by-pass said control means for connecting said cushioning cylinder-piston-assembly with an exhaust without affecting the pressure condition in said ejector cylinder-piston-assembly, whereby said movable element of said cushioning cylinder-piston-assembly may selectively be reciprocated during a working cycle without substantial cushioning effect irrespective of the operation of said movable element of said ejector cylinder-piston-assembly as ejector during the said cycle.

9. In combination in a press, a main cylinder, a fluid operable press ram reciprocable in said main cylinder to perform a pressing and a retraction stroke, a fluid operable member with a main area and an auxiliary area, control means for

admitting pressure fluid to said auxiliary area in response to a predetermined travel of said ram during the retraction stroke thereof to operate said member as ejector, check valve means responsive to the ejecting movement of said member to admit fluid to said main area, valve means normally in position to allow free escape of fluid at substantially no pressure from said main and auxiliary areas during the pressing stroke of said ram, thereby preventing said member from acting as cushioning plunger, means associated with said valve means for holding the latter in closed position during a complete cycle of said ram for preventing said free escape of fluid from said plunger, and means for relieving pressure from said plunger in excess of a predetermined pressure acting thereupon, thereby allowing operation of said plunger during one and the same cycle selectively as ejector only, or as cushioning plunger and ejector.

WALTER ERNST.
